UNITED STATES PATENT OFFICE

2,607,372

WIRE STRAPPING TOOL

Ernest White, Port Alice, British Columbia, Canada, assignor to Griplock, Inc., Hoboken, N. J., a corporation of Delaware

Application April 10, 1946, Serial No. 660,992

3 Claims. (Cl. 140—93)

1

This invention relates to a wire strapping tool which is designed for fastening around packages straps composed of wire, and it is particularly intended to be used in combination and cooperation with a wire strap which has been formed with one end turned back and coiled around the body of the wire, so that the knot may be made by passing the other end of the wire strap through the said coil and then crushing or flattening the coil so as to deform it and the parts of the wire therewithin into a firm interlocking engagement.

Machines for producing such straps are disclosed in United States patent application filed by John Sholtis, Jr., and Harold K. Embree on March 8, 1945, under Serial Number 581,688, now Patent No. 2,439,272; and in United States patent to W. N. Lurcott, No. 1,427,962, issued September 5, 1922. Previous tools for knotting the straps are set forth in United States patent application filed by Harold K. Embree and Burton L. Watt on February 3, 1945, under Serial Number 576,054, now Patent No. 2,442,679; and in United States patent to Burton L. Watt and James J. Smith, No. 2,124,991, issued July 26, 1938; as well as United States patent to Mark H. Stratton, No. 1,776,868, issued September 30, 1930; in the operation of which tools, simultaneously with the above described knotting of the strap, the excess of its free end is severed to improve the appearance and eliminate the long end which otherwise might present a hazard in subsequent handling and shipment.

An object of the invention is to provide such a device in which the crushing of the coil to form the knot is accomplished by jaw-like relative movement of cooperating elements.

Another object is to provide such a device in which one of the jaw elements is stationary and one movable.

Another object is to provide such a device in which the jaw action is progressive in its effect upon the coil as distinguished from direct crushing which contacts the whole coil at once.

Another object is to provide such a device in which the movable jaw element is pivoted and is arranged to have contact with the operating mechanism at a point located a greater distance from the pivot than is the jaw itself, whereby the effective crushing power is increased.

Another object is to provide such a device in which the movable jaw element has an elongated arm which is formed for roll and socket, or the like, engagement with the operating mechanism.

Another object is to provide such a device in

2

which the arm on the movable jaw element is actuated by a thrust bar, or the like, which has a swinging connection with a power driven reciprocating member, such as an hydraulic piston.

5 Another object is to provide such a device in which the line of travel of the piston, or the like, is substantially at right angles to the line of action of the movable jaw element.

Another object is to provide such a device 10 which is very compact in structure so as greatly to facilitate its handling in the confined spaces within which it is used.

A further object is to provide certain improvements in the form, construction, and arrangement of the parts whereby the above named and other objects are effectively attained.

A practical embodiment of the invention is represented in the accompanying drawing, in which

20 Fig. 1 represents a top plan view of the tool; Fig. 2 represents a front end elevation thereof, showing a portion of the strap in position to be crushed for knotting;

Fig. 3 represents a rear end elevation;

25 Fig. 4 represents a section taken in the plane of the line IV—IV of Fig. 1, looking in the direction of the arrows;

Fig. 5 represents a view similar to Fig. 4, with certain parts in different positions;

30 Fig. 6 represents a section taken in the plane of the line VI—VI of Fig. 3, looking in the direction of the arrows; and

Fig. 7 represents a detail view of the ends of the wire ready to be crushed for knotting, with the free end that is to be severed shown as bent to a position substantially at right angles with the remainder to facilitate the severing.

The tool constituting the subject matter of this invention is of that class designed for cooperative use with wire straps such as hereinabove described, in order rapidly and securely to bind packages of various kinds, but, more especially, packages composed of material that may be compressed, as by the platen of an hydraulic press,

45 while the strap is knotted around the package, and will expand upon release of the compression so as to tension or tighten the strap. Paper pulp is a good illustration of such a material. The tool is adapted to be associated with a compressed package around which such a wire strap has been manually placed, and thereupon to deform the coil and contacting parts of the strap by a crushing pressure which establishes the knot and causes the strap firmly to bind the package with

50 the desired tension after the compressive pres-

sure has been released and the package has expanded.

Those portions of the strap which cooperate with and are acted upon by the tool are well shown in Fig. 7, where the body of the strap is denoted by A, its coil by B, and its end which is passed through the coil for knotting and subsequent severing of the excess is marked C. It will be understood that the broken away part of the strap which is not seen in the figure consists of the main body thereof which has been passed around the package before the tool has been placed in operative position.

Referring now to the drawing, the tool comprises a casing, denoted generally by 1, which has a cylindrical body portion 2 developed at one end into a depending fixed jaw 3, that is cut away to form a support for an anvil plate composed of a pair of oppositely tapered slabs 4 and 5. The anvil plate is fixed in position by screw bolts 6, 6 which traverse the jaw 3, pass freely through holes 7, 7 in slab 4 and are threaded into slab 5. As the holes 7, 7 are considerably larger than the cross section of the screw bolts 6, 6, the elevation of the slab 5 can be varied by moving the slab 4 to the right or left in Fig. 2, whereby adjustment of the anvil plate can be effected and wear compensated. Slab 5 is preferably composed of hardened steel.

Journals, one of which is shown and marked 8, are formed at each side of the fixed jaw 3 fitted to receive bushings, one of which is shown and marked 9, that constitute bearings for the trunnions, one of which is shown and marked 10, of a pivoted movable jaw 11.

As a result of this construction, the jaw 11 is pivoted at each side of the fixed jaw 3 so that it can be oscillated toward and from the anvil plate in the operation of the tool, to accomplish which oscillation, the jaw 11 is provided with an elongated curved arm 12 which has its extremity 13 rounded in order to fit into a semi-circular groove 14 that is fashioned in one end of a thrust bar 15 which has its other end rounded for reception in a substantially semi-circular groove 16 that is formed in the lower end of a piston 17. In describing the grooves 14 and 16 as semi-circular or substantially semi-circular, it is meant that they have that form in cross section, the grooves as such being straight.

From the immediately foregoing description, it will be evident that motion of the piston 17 to the left in Figs. 4 and 5 will cause the movable jaw 11 to rock on its trunnions 10 toward the anvil plate composed of the slabs 4 and 5, which motion serves to crush the coil of the strap as will be hereinafter described. Fig. 4 of the drawing shows the parts in position before this functional motion of jaw 11, and Fig. 5 shows the position of the parts upon the completion of said motion. In order to retract the jaw 11 from the position shown in Fig. 5 to that shown in Fig. 4, it is provided with a lug 18 to which is connected one end of a retractile coil spring 19 which has its other end connected to a hook 20 that is formed on the end of a bolt 21 fixed in the cylindrical portion 2 of the casing 1.

In order to accomplish severing of the excess free end C of the wire strap, a pair of cutters 22, 23 is provided, the former of which is set into a slot in the fixed jaw 3 and removably secured therein by a screw 24, while the latter is similarly set in a slot in the movable jaw 11 and removably held therein by a screw 25. Upon the operative motion of the jaw 11, the cutter 23 is

brought into cooperative relationship with the cutter 22, and will sever the free end C of the strap which is located between the cutters as will be hereinafter explained.

5 The piston 17 is provided with the usual packing 26, which may be composed of a fibrous substance or any other suitable material as is well understood by those skilled in the art, the said packing being held in position by a cap plate 27 and screw bolt 28. This packing 26 serves to provide a substantially fluid tight engagement of the piston 17 with the inner wall of the cylindrical portion 2 of the casing 1 in order to render effective an hydraulic means for actuating the piston, which means will now be described.

A substantially cylindrical casing cap 29 has a reduced end which is threaded into the cylindrical portion 2 of the casing as indicated at 30, which cap has a threaded bore 31 that receives the threaded end of a conduit 32 which leads from a suitable source of hydraulic power (not shown) such for instance as any well known or approved form of pump or the accumulator of an hydraulic press. A valve seat 33 is also threaded into the bore 31 and cooperates with the ball head 34 of a valve which has a stem 35 that rests in a reduced portion of the bore 31 and is designed for operation by a manually actuated spindle 36 which is mounted transversely in the casing cap 29 and secured in position by a nut 37 with stuffing gland 38. A handle 39 is secured to the protruding end of the spindle 36 by a screw bolt 40 for manual actuation.

The spindle 36 is circular in cross section but is provided with a flattened portion 41 in line with the valve stem 35 which flattened portion, when in register with the said valve stem, will permit the ball head 34 to have closing contact with the valve seat 33 so as to prevent entrance 40 of the hydraulic fluid, such as oil, from the source of power. When, however, the spindle 36 is turned so that its circular surface registers with the valve stem 35, the ball head 34 will be unseated and the hydraulic fluid may enter through conduit 32, bore 31, valve seat 33, flattened portion 41 of spindle 36, and thence through channel 42 formed in casing cap 29 in line with bore 31, into the cylindrical portion 2 of the casing 1 and hence into operative contact with piston 17. The channel 42 is enlarged at its inner end, as indicated at 43, in order better to provide fluid contact with the piston 17 when the latter is in its retracted position illustrated in Fig. 4.

An outlet conduit 44 is threaded into a bore 45 formed in the casing cap 29, which bore is in line with a second flattened portion 46 on spindle 36. A channel 47 is also formed in the cap 29 in line with the flattened portion 46, and a valve seat 48 is threaded into the said channel for cooperation with the ball head 49 of a valve which has a stem 50 designed for cooperation with the spindle 36 and the flattened portion 46 thereon. When the stem 50 is in register with the flattened portion 46, the valve is closed by the seating of the head 49 on the seat 48; and when the stem is in register with the circular surface of the spindle 36, the ball 49 is unseated and the valve is open. A collar 51 is threaded into the end of the channel 47 to prevent dislodgment of the parts therewithin.

In order to provide for circulation of the hydraulic fluid when the spindle 36 is turned so that the ball head 34 is seated to prevent ingress of the hydraulic fluid and the tool is, therefore, idling, a by-pass 52 is formed in the casing cap

29 and leads from the bore 31 at a point outside of the ball head 34 to the channel 47 at a point inside the ball head 49 which latter is, in this position of the parts, represented in Fig. 4, the hydraulic fluid entering through conduit 32 will travel through by-pass 52 to channel 47, through valve seat 48, flattened portion 46, bore 45, and outlet conduit 44 back to the source of hydraulic power, which circulation may continue indefinitely without any operative effect upon the tool. When the ball head 34 is unseated so as to permit ingress of the hydraulic fluid to the piston 17 for operating the tool, the ball head 49 is seated, thereby rendering the by-pass inoperative, as illustrated in Fig. 5.

The spindle 36 is frictionally held in different positions to which it is manipulated by a brake-plunger 53 which is set in a bore formed in the cap 29 and opening to the spindle 36, the said brake-plunger being controlled in its effect by an adjustable screw plug 54 and an intervening yieldable pad or washer 55. A recess 56 is formed in the inner face of casing cap 29 to accommodate the head of screw 28 when the piston 17 is retracted.

In order to prevent excessive hydraulic pressure upon the piston 17, an adjustable vent is provided which consists of a screw bolt 57 that is threaded into a bore 58 formed in the cap 29 and forms a seat for one end of an expansion coil spring 59 which has its other end bearing upon a ball valve 60 that serves to open and close communication through a pair of ducts, one of which marked 61 leads to the interior of cylindrical portion 2 of the casing while the other, marked 62, leads to bore 45. By adjusting the screw 57 the tension of the spring 59 may be varied with corresponding variation in the degree of hydraulic pressure at which the vent will become effective.

A gasket 63 is interposed between portion 2 of the casing and the cap 29 to make the joint fluid tight. The angular by-pass 52 may be fashioned in the cap 29 by suitable drilling and plugging, all of which is so well understood by those skilled in the art as to call for no illustration or specific description. A safety guard or shield 64 is secured to the casing by screws 65, 66 to protect the movable jaw and associated parts as well as the operator, and screws 66, 66 are threaded into the trunnions 10 to hold the bushings 9 in position.

In operation, one of the wire straps is laid in a suitable groove formed in the top of the lower platen of a press, the package to be bound by the strap is positioned on the platen in the desired relationship to the wire strap, the upper platen of the press is lowered to compress the package, the tail end of the strap is brought upwardly along one side of the package and threaded through a groove formed in the face of the upper platen, so that the coiled end of the strap and the tail end thereof are exposed to the operator at one side of the package. The operator then passes the tail end of the strap through the coil on the other end thereof, pulls the tail end therethrough a predetermined distance, and bends it substantially at right angles, as illustrated in Fig. 7. The operator then positions the tool against the side of the package with its fixed jaw 3 between the strap and the package and with the coil B lying on the anvil plate composed of the slabs 4 and 5 while the bent end C lies between the blades 22 and 23, as illustrated in Figs. 2 and 4. The oper-

ator then seizes the handle 39 and turns the spindle 36 so as to permit an ingress of the hydraulic fluid to the piston 17, as hereinbefore described. An hydraulic force thus released will move the piston from the position shown in Fig. 4 to the position shown in Fig. 5, with the result of causing the movable jaw 11 to swing on its trunnion pivots from the position shown in Fig. 4 to the position shown in Fig. 5 with the result of crushing the coil on the wire strap and severing the free end. This crushing of the coil will deform it and the parts of the strap lying therewith so as to establish a strong and dependable knot or fastening. The operator then turns the handle 39 so as to rotate the spindle 36 and permit the fluid to exhaust through conduit 44 while the spring 19 moves the jaw 11, the thrust bar 15, and the piston 17 to retracted position. The tool may then be removed from its cooperative relationship with the package and the upper platen of the press may be raised to permit the package to expand and thereby tension the strap firmly around it.

While the tool is comparatively small and may be handled by an operative, it is convenient to have the same suspended, as by a counterbalanced rope, adjacent the press, so that the operative need merely swing it into position and actuate it as above described without being required manually to support the weight of the tool.

As presses, e. g. hydraulic, with grooves in their platens as above described are well known in this art, there is deemed to be no occasion for illustration or further description thereof; nor is there believed to be need for describing or showing how the packages are placed upon the lower platen of such a press because that may be done manually or by conveyer, as is familiar in this industry. It may be added that the platens of presses for the purpose hereinabove mentioned commonly have grooves extending in both directions thereacross so that wire straps may be placed in two directions at right angles to each other around packages, if desired.

As it is customary in practice for a large number of packages of the same material and size to be bound in succession, the operator will be provided with straps of suitable strength and length for the purpose, which straps may, if desired, be marked to indicate how far the operator should pull the free end C through the coil B before bending the end at right angles, as illustrated in Fig. 7. In this way the knotted strap will be of the same length for the successive packages and the expansion of the packages following elevation of the upper platen of the press will lead to uniform tension of the straps around all the packages.

The strap manufacturer, upon being provided with the necessary data as to the character of the package and the transportation and handling through which it is destined to pass, can determine the size and strength of the wire strap best suited to the purpose as well as the degree to which the coil of the strap and the parts of the strap therewith should be crushed and deformed in order to establish an adequate knot without danger of rupturing or fracturing the strap through excessive crushing pressure. Thus the tool operator will know what degree of hydraulic pressure should be used in the tool for the various occasions of its use and can not only take such measures as are available for controlling the pressure received by the tool from the source of supply, but can very accurately predetermine and

fix the pressure permitted to act upon the piston 17 by regulating screw 57 which controls the tension of the spring 59 in the excess pressure vent. The adjustability of the slabs 4 and 5 of the anvil plate, hereinabove mentioned, usefully cooperates in predetermining the degree to which the strap coil is crushed.

Outstanding advantages of this invention include the progressive manner in which the crushing pressure is applied to the strap by the movable jaw 11 which, because of its relationship to the anvil plate slabs 4, 5 and its arcuate motion, engages the coil of the strap in the first instant at one side thereof and then gradually assumes a position of direct downward pressure substantially parallel to the anvil plate. Such an action affords the strap more time in which to accommodate itself to the distortion involved in the crushing action, and lessens the liability of fracturing the wire. Again, the fact that the force of the piston is exerted substantially at right angles to the direction of movement of the jaw 11, enables advantage to be taken of the elongated arm 12 on the said jaw whereby the actual pressure exerted by the piston is greatly magnified in the crushing power of the jaw. This arrangement of the parts also leads to compactness of the tool which is a practical virtue of importance mainly because of the restricted space in which the tool frequently, if not usually, has to operate. Again, the rugged construction of the thrust bar 15 and its roll and socket engagement with the piston and arm 12 of the movable jaw imparts an extremely effective operative contact between the straight line reciprocating piston and the arcuately oscillating jaw. Between its use in connection with successive packages, the handle 39 may be moved so as to turn the spindle 36 into its inoperative position and the tool may be permitted to idle, so to speak, with the hydraulic fluid entering the conduit 32, traversing the bypass 52 and flowing out through the conduit 44, without affecting in any way the piston 17 or parts connected therewith.

While the operation of the tool embodying the present invention has been set forth in connection with straps that have been merely manually tensioned around packages, it will be clear that the tool is adaptable to the knotting and severing of straps which have been subjected to tensioning devices, as is reflected by the patent application 576,054 and Patents 2,124,991 and 1,776,868, previously mentioned.

It will be understood that various changes may be resorted to in the form, construction, material, and arrangement of the parts without departing from the spirit and scope of the invention; and hence I do not intend to be limited to details herein shown and described except as they may be included in the claims or required by disclosures of the prior art.

What I claim is:

1. A tool of the character described comprising, a fixed jaw, a pivoted crushing jaw, means on the fixed jaw for supporting portions of a strap to be crushed with the said portions lying transversely to the plane of movement of the pivoted jaw, and fluid actuated means for causing the operative face of the pivoted jaw to move from an angular relationship to a substantially parallel

relationship with respect to the supporting means on the fixed jaw, whereby the effect on the portions of the strap being crushed is progressive, said fluid actuated means including an arm on said pivoted jaw of greater length than the distance of the jaw from its pivot, a piston, and a thrust bar intermediate said arm and said piston and having a swinging engagement therewith.

2. A tool of the character described comprising, a fixed jaw, a pivoted crushing jaw, means on the fixed jaw for supporting portions of a strap to be crushed with the said portions lying transversely to the plane of movement of the pivoted jaw, and fluid actuated means for causing the operative face of the pivoted jaw to move from an angular relationship to a substantially parallel relationship with respect to the supporting means on the fixed jaw, whereby the effect on the portions of the strap being crushed is progressive, said fluid actuated means including an arm on said pivoted jaw of greater length than the distance of the jaw from its pivot, a piston, and a thrust bar intermediate said arm and said piston and having a roll and socket engagement therewith.

3. A tool of the character described comprising, a fixed jaw, a pivoted crushing jaw, means on the fixed jaw for supporting portions of a strap to be crushed with the said portions lying transversely to the plane of movement of the pivoted jaw, and fluid actuated means for causing the operative face of the pivoted jaw to move from an angular relationship to a substantially parallel relationship with respect to the supporting means on the fixed jaw, whereby the effect on the portions of the strap being crushed is progressive, said fluid actuated means including an arm on said pivoted jaw of greater length than the distance of the jaw from its pivot, a piston, and a thrust bar intermediate said arm and said piston and having a roll and socket engagement therewith, the free end of said arm and one end of said thrust bar being rounded and the said piston and the other end of said thrust bar being grooved for the purpose of establishing said roll and socket engagement.

ERNEST WHITE.
